UNITED STATES PATENT OFFICE.

THOMAS F. WHELAN, OF KIRKWOOD, MISSOURI, ASSIGNOR TO SAVODAY RACK COMPANY, OF ST. LOUIS, MISSOURI, A CORPORATION OF MISSOURI.

DEVICE FOR TREATING SHOES.

1,157,482.

Specification of Letters Patent. Patented Oct. 19, 1915.

Application filed May 11, 1911. Serial No. 626,536.

To all whom it may concern:

Be it known that I, THOMAS F. WHELAN, a citizen of the United States, residing at Kirkwood, Missouri, have invented a certain new and useful Improvement in Devices for Treating Shoes, of which the following is a full, clear, and exact description, such as will enable others skilled in the art to which it appertains to make and use the same, reference being had to the accompanying drawings, forming part of this specification.

My invention relates to an apparatus for treating shoes during the process of their manufacture, and relates more particularly to an apparatus for moistening the toe portion of shoe uppers to facilitate their being drawn over the last into proper form.

Some of the objects of the present invention are to provide an apparatus of the sort described which has a large capacity, which effectively protects portions of the shoes not designed to be moistened, which may be operated at a temperature sufficiently low to insure against burning or killing the leather by heat; which is compact in form and may be economically manufactured; and which may be operated at low expense.

In the drawings: Figure 1 shows, in perspective, a shoe rack provided with a plurality of compartments embodying the present invention; Fig. 2 shows an end elevation of one of the casings or compartments; Fig. 3 is a view in vertical cross-section through one of the shoe receiving casings shown in Fig. 1; Fig. 4 is a view in vertical longitudinal section through one of the shoe compartments, partly broken away, and Figs. 5, 6, 7, 8, and 9, are views in vertical cross-section through various modified forms of shoe compartments.

Referring to the drawings more specifically, it will be understood that 1 indicates generally a shoe rack comprising a series of posts 2 which support shelves or shoe supporting members 3. In coöperative relationship to each shelf is disposed a casing or compartment 4 of suitable material, such as sheet iron, and formed with the side walls 11, end walls 13 and a top or upper wall 13' which may be lined with asbestos or other suitable material.

The casings or compartments are generally in the form of a substantially rectangular box or housing having the bottom por-

tion shaped to form a longitudinally extending recess or trough 5, and the top portion depressed toward its medial line to form a sort of division between the respective sides of the casing. The opposite vertically disposed walls 11 of the casing are provided with shoe-receiving apertures 12 which preferably are finished around their edges with some suitable non-abrasive material, such as felt, which fits around the shoes and suitably limits the discharge of vapor from the casing.

Extending longitudinally within the trough 5 is a suitable heating element 6 which may be in the form of an electrical resistance member, or a perforated steam pipe, as illustrated in Fig. 9. The ends of the trough portion 5 may be provided with suitable openings 14, coöperating with which is any desired means of closure such as a rotary valve or damper 15.

If desired the compartment 4 may be divided, by means of partitions 16, (see Fig. 4) into smaller compartments or sections for the reception of one or more shoes, or if desired, the openings 12 may be provided with a suitable gate or closure 20 (see Fig. 8), which is hinged at 21 and operable by a weight 22 which causes the gate 20 to swing upwardly to close the opening 12 and prevent the escape of vapor whenever such opening is not occupied by the toe of the shoe. The mountings of the casings 4 may consist of the depending ears 9 in which are seated the set screws 10 which are adapted to coöperate with the ends of the shelves 3, thereby holding the casings firmly though removably in position.

It is believed that operation of the device will be obvious from the foregoing description and the illustrations.

It will be understood, the trough or recess 5 being filled with water to the desired level, that the shoes whose uppers are to be steamed or moistened, are placed with the toes projecting through the apertures 12, the shoes being supported on the shelves or supports 3. The heat generated or introduced by the heating element 6 causes a vaporization of the water surrounding it, and this moist vapor arising from the trough 5 is guided or deflected onto the toes of the shoes by the upper wall 13' or top of the compartment. This humid vapor operates to moisten and soften the box toe materials and the

leather of the upper at the toe end of the shoes, so that they may be drawn over the last smoothly and easily, without injury to the stock. It being practically impossible to 5 make an air-tight fit between the different shoes inserted in the apparatus and the edges of the openings 12, some outside air will enter between the shoe soles and these openings and flow in and over the heating coil, 10 absorb heat, rise and circulate about the shoe tips and escape from the upper portions of the openings. This air will serve to temper the steam, more or less, and thus avoid injury to the leather. If desired, in instances 15 where the steam introduced by the steam pipe form of heating element, as illustrated in Fig. 9, is particularly dry, it may be found desirable to place waste 25 about it in the trough 5 so as to break it up to render its 20 passage through the water in the trough more slow.

It will be seen from the foregoing that the device includes a vapor-generating trough or chamber adapted for the reception of a 25 fluid, and containing a suitable heating element for vaporizing the fluid, and laterally disposed shoe-receiving compartments having communication with the vapor-generating compartment, the said shoe-receiving 30 compartments being adapted to receive the toes of shoes in such position that they may be reached by vapor in the shoe-receiving compartments, the compartments being so formed as to afford protection for portions 35 of the shoe which it is not desired to moisten. This provides a steaming device of large capacity particularly useful in large factories and one which is easily and safely operable by the shoe workmen.

40 I am aware that minor changes may be made in the arrangement, construction and combination of the various elements of my device, without departing from the spirit of my invention, the scope of which is set forth 45 in the accompanying claims.

What I claim is:

1. A device for treating shoes, comprising a shoe-receiving compartment adapted to receive the toe portions of shoes, a fluid-containing compartment having communication therewith and adapted to contain a fluid, and a heating device disposed in said fluid-containing compartment and adapted to vaporize a fluid therein; portions of said shoe-receiving compartment being shaped and arranged to direct vapor arising from said fluid-containing compartment downwardly upon the portions of shoes contained in said shoe-receiving compartment.
2. A device for treating shoes, comprising a shoe-receiving compartment, a chamber adapted for the reception of fluid communicating therewith, vapor-generating means in said chamber, said shoe-receiving compartment being provided with apertures for the

reception of a portion of a shoe, said compartment also having a portion adapted to guide vapor arising from said chamber downwardly upon the portions of shoes contained in said compartment.

3. A device for treating shoes, comprising a chamber adapted for the reception of liquid, vapor-generating means located therein, a shoe-receiving casing provided with apertures in opposite sides thereof adapted for the reception of a portion of a shoe, and shoe supports disposed in co-operative relationship to said apertures; said shoe-receiving casing having communication with said chamber by virtue of which vapor may be supplied to said casing from said chamber.

4. A device for treating shoes, comprising vapor-generating means, shoe-receiving compartments disposed laterally at either side of said means and having communication therewith, and shoe supports disposed in co-operative relationship to said shoe-receiving compartments.

5. A device for treating shoes, comprising a casing having a medially disposed trough for the reception of fluid, vapor-generating means therein, said casing being formed with shoe-receiving compartments disposed laterally at either side of said trough and adapted for the reception of portions of shoes, and supports for shoes disposed in co-operative relationship to said casing.

6. A device for treating shoes, comprising a casing having a portion adapted for the reception of a fluid, and vapor-generating means therein, said casing being provided with an aperture for the reception of a shoe portion, and a portion of said casing being shaped to guide vapor arising from said generating means downwardly upon a shoe portion inserted through said aperture.

7. In a device for treating shoes, a shoe-receiving compartment provided with an aperture through which a shoe portion may be inserted, means for supplying said compartment with vapor, and means for closing said aperture to prevent the escape of vapor therethrough.

8. In a device for treating shoes, a shoe-receiving compartment provided with an aperture through which a shoe portion may be inserted, means for supplying said compartment with vapor, and a closure for said aperture, which closure is displaceable by a shoe portion inserted through said aperture.

9. In a device for treating shoes, a shoe-receiving compartment provided with an aperture adapted for the reception of a shoe portion, means for supplying said compartment with vapor, and means operating to close said aperture upon the withdrawal of a shoe portion therefrom.

10. In a device for treating shoes, a shoe-receiving compartment provided with an aperture through which a shoe portion may

be inserted, and means for supplying said compartment with vapor, said compartment being provided with means disposed in co-operative relationship to said aperture adapted to prevent the free discharge of vapor about a shoe portion disposed therein.

11. A device for treating shoes in the form of a shoe rack having supports for shoes disposed one above another, shoe-receiving compartments disposed in co-operative relationship to said supports, and means for supplying said compartments with vapor.

12. A device for treating shoes, comprising a casing having oppositely arranged shoe-receiving compartments provided with apertures in the sides thereof adapted for the reception of shoe toes, and a trough ar-

ranged between said compartments for containing shoe treating means.

13. An apparatus of the class described comprising a pair of oppositely arranged compartments having apertures to receive the toe portions of shoe, a support for shoes adjacent and outside each compartment, and a trough arranged intermediate said compartments and adapted to contain shoe-treating means.

In testimony whereof I hereunto affix my signature in the presence of two witnesses, 30 this 8th day of May, 1911.

THOMAS F. WHELAN.
